RAILWAY TRUCK

Filed April 13, 1925

UNITED STATES PATENT OFFICE

CLAUS J. W. CLASEN, OF DAVENPORT, IOWA, ASSIGNOR TO THE BETTENDORF COMPANY, OF BETTENDORF, IOWA, A CORPORATION OF IOWA

RAILWAY TRUCK

Application filed April 13, 1925. Serial No. 22,597.

This invention relates to improvements in railway trucks.

The general object and nature of the present invention is to provide means for increasing the spring capacity of a railway truck without proportionately increasing the wheel base or depth, or appreciably increasing the weight of such truck, or impairing the strength thereof, as set forth in my related applications filed of even date herewith.

The purpose of the present invention is generally similar to that contemplated in certain of my related cases above mentioned, that is, to increase the longitudinal extent of the spring rest of an integral truck frame, by spacing the guide columns, or portions thereof, a greater distance apart proportionate to the dimensions of the side frame than is ordinarily the case, in conjunction with novel reinforcing means for bracing the frame to compensate for the increased longitudinal extent of the spring rest which reinforcing means are arranged to provide a safety pocket for the springs to prevent loss thereof should they become dislodged.

A construction of this character naturally requires a widened bolster to bear upon the increased number of spring units, and since many foundries do not have flasks or other facilities large enough to cast bolsters of sufficient width, I provide means by which bolsters of ordinary width may be utilized in connection with the side frames, having guide columns which are spaced apart a greater distance than usual. In effecting this result I utilize filler means which have portions interposed between the sides of the bolster, the guide columns and the springs, such means being arranged so that the bearing stresses between the parts are transmitted uniformly from the bolster to all portions of the increased spring cluster, such means being connected to the bolster and endwise insertable therewith between the guide columns, in conjunction with a removable key for retaining the filler means in operative engagement with the side frame.

Other and further objects of the invention will more clearly appear from the description and claims hereinafter following.

In the drawings, Figure 1 is a side elevation of the major portion of a side frame, 55 of the character contemplated by my invention. Figure 2 is a top plan partial sectional view of the invention with portions of the frame broken away to more clearly disclose the disposition of the parts; and 60 Figure 3 is a transverse sectional view of the invention on the line 3—3 of Figure 1.

Referring to the drawings, in the construction illustrated, there is shown a side frame of a truck, and in this connection I 65 have deemed it necessary to illustrate the parts on one side of the truck only, it being understood that the other side of the truck will be correspondingly made.

The side frame illustrated comprises a 70 compression member 10, a tension member 11, and journal boxes 12, which are preferably cast integrally with the side frame.

The invention broadly includes guide 75 columns A—A of novel formation, shown cast integrally with the compression member and tension member; a spring rest B; reinforcing means C; a spring cluster D; a bolster E; and a pressure transmitting device and filler F.

The guide columns A are of peculiar formation, said guide columns being spaced a relatively great distance proportionately to the dimensions of the side frame, said guide columns also including relatively narrowly 85 spaced upper portions 13 and lower portions 14, the inner guide faces of which are undercut or recessed as indicated at 15, thereby providing the spring rest B which is of greater longitudinal extent than the width 90 of the bolster E, the spring rest B extending laterally beyond the tension member 11 as shown.

Preferably formed integrally with the lower portions 14 of the guide columns A 95 and the walls 16 defining the upper portions of the recesses 15 at either side of said columns, are the connecting walls C, such walls preferably being formed integrally with the spring rest at the bottom and following the 100

outlines thereof, such walls merging into the portions 16 of the upper portions 13 of the guide columns. It will be appreciated that the members C, due to their disposition, act as combined compression and tension means for bracing the frame and particularly the tension member 11 against fracture so as to compensate for the additional length of the spring rest of the side frame.

10 The spring cluster D preferably comprises seven spring units arranged as illustrated in the drawings, the end units 18 of such cluster being disposed in the recesses 15 formed in the guide columns, such springs 15 being of the ordinary type used in trucks of this character, or other suitable resilient means.

In a construction of this character, the bolster E necessarily must be insertable end-20 wise between the portions 13 of the guide columns A, and since the space between the portions 13 of the guide columns is considerably greater than that ordinarily provided, a wider bolster must be utilized in connection with a frame of this character in order to afford an increased surface uniformly bearing upon the additional spring elements as well as those ordinarily provided. The production of bolsters of the additional 25 width is sometimes impracticable, due to the fact that many foundries do not have flasks large enough for this purpose, and it becomes important to provide means for utilizing bolsters which are of less width than 30 the space between the guide columns and which may be produced in the ordinary sized flasks, and I accomplish this result in the manner which will now be described.

The bolster E, which is of a width less 40 than the distance between the portions 13 of the columns A, is provided with lugs 19 spaced some distance from the end of the bolster, and with lugs 20 adjacent the outer end of the bolster.

45 Interposed between the bolster and the spring cluster is the pressure transmitting device F. Such device comprises a member having a bottom portion 21 extending the entire distance between the portions 13 of 50 the guide columns and adapted to have a snug sliding fit therewith, such portion bearing uniformly upon the top surfaces of all of the spring units of the spring cluster D, as clearly shown in the drawings. The member F is provided with end walls 22 having 55 lugs 23 which co-operate with the lugs 19 and 20 formed on the bolster, the width of the end walls 22 being such as to snugly fill the space between the sides of the bolster 60 and the faces of the guide surfaces of the guide columns A. The inner portions of the walls 22 are provided with laterally extending lugs 24 adapted to engage the inner surfaces of the guide columns A. The outer 65 ends of the walls 22 are connected by a

70 wall 25 disposed on the outer side of the end of the bolster, such wall being provided with a key-way 26 for the reception of a key 27, held in position by any suitable means such as the bolts 28, the ends 29 of such key being arranged to slide on the outer surfaces of the portions 13 of the guide columns.

75 In conjunction with a side frame of this character, I provide a special type of spring plate and spring plank which is more particularly referred to in connection with my related applications aforesaid. One type of such arrangement is illustrated in Figure 3 80 of the drawings. In this figure, the inner connecting walls C are provided with spaced apertures 30, through which project lugs 31 formed upon the spring plate 32 disposed upon the spring rest B, the spring cluster being supported upon the spring plate 32. The spring rest B is provided on its inner side with an extension 33 having a plurality of bosses or abutments 34 formed thereon adapted to receive apertures 35 in one end of the spring plank 36 the 90 walls of the apertures 35 providing abutments inter-engageable with the bosses 34, the lugs 31 of the spring plate being arranged to bear upon the inner end 37 of the spring plank between the lugs 33, thereby 95 providing an efficient connection for the spring plank 36, it of course being understood that the other end of the spring plank is secured to the respective side frame in a similar manner.

100 By this arrangement, when it is impracticable to provide a bolster of sufficient width to bear uniformly upon the increased spring cluster, it will be evident that by utilizing the cradle or filler member F that 105 a comparatively narrow bolster may be used in connection with a side frame of this type. In this construction, the cradle is applied to the bolster before the insertion thereof between the guide columns, by engaging the 110 lugs 23 of the cradle with the lugs 19 and 20 on the bolster. The cradle in this manner snugly fits over the end of the bolster and is of a width which may be thus inserted between the portions 13 of the guide 115 columns before the key 27 is applied, the wall 21 of the cradle resting uniformly upon the spring units of the spring cluster D. The key 27 is then inserted through the key-way 26 provided in the end portion 25 120 of the filler device F and the bolts 28 secured in position. The filler member is thus held against lateral movement with respect to the guide columns A by means of the key 29, and the integral lugs 24, bearing on the 125 outer and inner surfaces, respectively of the guide columns, and such filler member is securely and detachably connected with the bolster E by the inter-engagement of the lugs 23 and lugs 19 and 20 on the members. 130

The bearing stresses of the narrow bolster are thus transmitted uniformly by the bottom wall 21 and side walls 22 to all the spring units of the spring cluster D, and the 5 walls 22 occupy the space between the sides of the bolster and the guide columns.

The connecting members C reinforce the entire frame structure, such means acting as a beam interposed between the lower portions of the guide columns A and connected 10 to the tension member 11, thereby serving as a combined compression and tension member, the walls C being arranged so as to provide a safety pocket for the spring cluster 15 to prevent loss of the spring units.

The spring plank arrangement is similar to that disclosed in my related applications and is of the type which is particularly adapted for use with a side frame of the 20 character contemplated therein, being quickly detachable when desired, and at the same time securely held in position by reason of the fact that the entire pressure exerted by the spring cluster is transmitted to the retaining lugs for holding the end of the plank in engagement with the bosses thereon.

While I have herein shown and described what I now consider the preferred manner of carrying out my invention, the same is 30 merely illustrative and I contemplate all changes and modifications that come within the scope of the claims appended hereto.

What I claim is:

1. In a railway truck, the combination 35 with a bolster; of a side frame including a compression member, a tension member, and guide columns spaced apart a distance greater than the width of said bolster; a spring cluster of greater extent than the width 40 of said bolster; and means detachably associated with said bolster and interposed between said bolster, said guide columns, and said spring assembly to transmit the bearing stresses from the bolster to all portions 45 of the spring cluster, said interposed means having elements adapted to engage the inner and outer surfaces of said guide columns to operatively connect said bolster and said guide columns, certain of said elements being detachable.

2. In a railway truck, the combination 50 with a bolster; of a side frame including a compression member, a tension member, and guide columns; a spring cluster and 55 filler means detachably associated with said bolster and interposed between said bolster and said guide columns said filler means being provided with elements adapted to engage spaced portions of said guide columns 60 for operatively connecting said filler means with said columns, certain of said elements being detachable.

3. In a railway truck, the combination 65 with a bolster; of a side frame including a compression member, a tension member, and

guide columns; a spring cluster; filler means interposed between said bolster and said guide columns for operatively connecting the same, said filler means and said bolster being provided with detachable interlocking 70 abutments for retaining said bolster against endwise movement relative thereto; and detachable means for retaining said filler means in operative relation with said guide columns.

4. In a railway truck, the combination 75 with a bolster; of a side frame including a compression member, a tension member, and guide columns; a spring cluster; interposed means providing a portion extending along 80 the under surface of said bolster and other portions disposed between the guide columns and the side of said bolster; means connecting said interposed means with said bolster; and an element detachably carried by said 85 interposed means for connecting the latter to said guide columns.

5. In a railway truck, the combination 90 with a bolster; of a side frame including a compression member, a tension member and guide columns; a spring cluster, said guide columns being recessed for the accommodation 95 of certain of said spring units; means interposed between said bolster, said guide columns and said spring cluster to transmit the bearing stresses between the respective bearing surfaces of such elements; and removable means associated with said interposed means for connecting the latter to 100 said guide columns.

6. In a railway truck, the combination 105 with a bolster; of a side frame including a compression member, a tension member, and guide columns; a spring cluster, said guide columns being recessed for the accommodation 110 of certain of said spring units; and means interposed between said bolster, said guide columns and said spring cluster to transmit the bearing stresses between the respective bearing surfaces of such elements, said interposed means being detachably connected with said bolster; and means detachably carried by said interposed means and providing elements engageable with said guide columns to maintain said interposed 115 means in assembled relation therewith.

7. In a railway truck, the combination 120 with a bolster; of a side frame, including a compression member, a tension member, and guide columns spaced apart a relatively great distance proportionate to said frame, and of greater extent than the width of said bolster; a spring cluster of greater extent than the width of said bolster; means interposed between said bolster and said guide 125 columns, and arranged to transmit the bearing stresses from the bolster to all portions of the spring cluster; and rigid means connecting the lower portions of said guide columns, said rigid means being disposed on 130

opposite sides of said guide columns and providing a pocket for the spring cluster.

8. In a railway truck, the combination with a bolster; of a side frame, including a compression member, a tension member, and guide columns; a spring cluster of greater extent than the width of said bolster; means interposed between said bolster and said guide columns, and arranged to transmit the bearing stresses from the bolster to all portions of the spring cluster; rigid means connecting the lower portions of said guide columns, said bolster and said interposed means being connected and endwise insertable between the upper portions of said guide columns; and means for detachably retaining said interposed means in operative relation with said guide columns.

9. In a railway truck, the combination with a bolster; of a side frame, including a compression member, a tension member, a spring rest and guide columns; a spring cluster; means interposed between said bolster and guide columns for transmitting the bearing stresses of said bolster to all portions of said spring cluster; rigid means connecting the bottom portions of said guide columns, said tension member and said spring rest; a spring plank detachably secured to said side frame exteriorly of said rigid means; and a spring seat having means extending through said rigid means and arranged to hold said spring plank in operative position.

10. The combination with a bolster, having an end portion; and means detachably interlocked with the end of said bolster, said means having elements adapted for co-operation with column guides of a side frame, certain of said elements being detachable.

11. In a railway truck, the combination with a bolster; of a side frame, including a compression member, a tension member, a spring rest and guide columns spaced apart a relatively great distance proportionate to said frame; a spring cluster disposed on said spring rest; means interposed between said bolster and guide columns for transmitting the bearing stresses of said bolster to all spring units of said cluster, said means having elements associated therewith adapted for engagement with the inner and outer faces of said guide columns, the outer of said means being detachably carried by said interposed means.

12. In a railway truck, the combination with a bolster having an end portion; of means detachably interlocked with the end portion of said bolster, said means having portions on opposite sides of the bolster to increase the effective width thereof; of a side frame, including a compression member, a tension member, a spring rest and guide columns and spring means disposed on said spring rest, said bolster and said de-

tachable means being insertable between said guide columns and co-operating with said spring means, and removable means carried by said detachable means for retaining said bolster end and said detachable means in operative relation with said side frame.

13. In a railway truck, the combination with a side frame including a compression member and a tension member; guide columns for said frame arranged to provide a spring rest therebetween; a spring assembly containing a plurality of spring units, said spring rest being flat throughout its extent, and adapted to accommodate said spring units in a common horizontal plane; a bolster cooperating with said side frame; and filler means interposed between the sides of said bolster and the guiding surfaces of said guide columns, and between said bolster and said spring assembly, said filler means being detachably connected with said bolster; and means removably carried by said filler means for connecting the latter to said side frame.

14. In a railway truck, the combination with a side frame including a compression member, a tension member, guide columns, and a spring rest; spring means arranged upon said spring rest; of a bolster cooperating with said side frame; of filler means interposed between the sides of said bolster and said guide columns and between the under-surface of said bolster and said spring means and secured to said bolster; elements detachably carried by said filler means for detachably connecting the latter to said guide columns; and a spring plank connected to said side frame said spring plank and frame including interengaging abutments detachable in one direction whereby said spring plank may be detached without destructive effect; said spring plank arrangement being normally held against detachment under the influence of the force exerted thereon by said spring means.

15. In a railway truck, the combination with a side frame including a compression member, a tension member, guide columns, and a spring rest; spring means arranged upon said spring rest, of a bolster cooperating with said side frame; of filler means interposed between the sides of said bolster and said guide columns and between the under-surface of said bolster and said spring means; a spring plank arrangement connected to said side frame and including means whereby said spring plank may be detached without destructive effect, and reinforcing means connecting said guide columns adjacent the bottom portions thereof, said spring plank arrangement extending across the plane defined by said reinforcing means.

16. A truck structure comprising a side frame having in combination, spaced bolster

columns having inner bearing surfaces and a connecting bottom portion, a truck bolster having its end vertically movable between said columns, a plurality of springs carried 5 on said bottom portion substantially at one level and disposed between said bearing surfaces, additional springs at each end of said springs having one side thereof disposed in said columns, and a spring cap plate adapted 10 to engage all of said springs and carrying the load of said bolster, said plate being movable in and between said columns.

17. A truck structure comprising a side frame having in combination, spaced bolster 15 columns having inner bearing surfaces and a connecting bottom portion, a truck bolster having its end vertically movable between said columns, a plurality of springs carried on said bottom portion substantially at one 20 level and disposed between said bearing surfaces, additional springs at each end of said springs having one side thereof disposed in said columns, and a spring cap plate disposed substantially in one plane adapted to 25 engage all of said springs and carrying the load of said bolster, said springs having their upper ends substantially at one level.

18. In a railway truck, the combination with a bolster, of a side frame including a 30 compression member, a tension member, a spring rest, and spaced guide columns, a spring cluster, pressure transmitting means interposed between said bolster and said 35 spring cluster, said means being recessed and receiving and partially surrounding the proximate end of said bolster and being laterally extended beyond the sides of said bolster to slidably engage said guide columns, and being arranged to transmit the 40 bearing stresses from the bolster to all portions of the spring cluster, and rigid means connecting the lower portions of said guide columns.

19. In a railway truck, the combination 45 with a bolster, of a side frame including a compression member, a tension member, and spaced guide columns, a spring cluster, pressure transmitting means interposed between said bolster and said spring cluster, said 50 means being recessed and receiving and partially surrounding the proximate end of said bolster and being laterally extended beyond the sides of said bolster to slidably engage said guide columns, and being arranged to 55 transmit the bearing stresses from the bolster to all portions of the spring cluster, and rigid means connecting the lower portions of said guide columns.

60 20. A spring cap for bolster springs comprising a normally horizontal portion adapted to seat on said springs, and upstanding lug portions adapted to engage the bolster guide columns on two sides thereof and fit 65 in corresponding notches in an associated

bolster to cooperate with inner guide lugs thereon for holding the bolster in place.

21. In a railway truck, the combination with a side frame, including a compression member, a tension member, guide columns, 70 and a spring seat, a bolster insertible endwise between said columns, said guide columns being spaced apart to accommodate the bolster and having relatively wider spaced vertically disposed recessed portions 75 for the reception of bolster springs; a spring cluster wider than the bolster receivable on said seat between said recessed portions of said columns; means wider than the bolster interposed between said bolster and spring cluster and bearing on said spring cluster for substantially its full width; and means for detachably retaining said bolster in cooperative relation with said side frame. 80

22. In a railway truck, the combination with a side frame, including a compression member, a tension member, and guide columns formed to provide increased width at their bottoms; of a bolster between said 85 guide columns; a spring cluster of greater extent than the width of said bolster; means interposed between said bolster and said spring assembly to transmit the bearing stresses from the bolster to all portions 90 of the spring cluster; and rigid means connecting the widened portions of said guide columns. 95

23. In a railway truck, the combination with a side frame, including a compression 100 member, a tension member, and guide columns spaced a greater distance at the bottom than at the upper portions thereof; of a bolster between said guide columns; a spring cluster of greater extent than the width of said bolster; means interposed between said bolster and said spring cluster 105 to transmit the bearing stresses from the bolster uniformly to all portions of the spring cluster; and rigid means connecting the wider spaced portions of said guide columns, said rigid means being disposed on opposite sides of said guide columns and providing a pocket for the spring cluster. 110

24. In a railway truck, the combination with a side frame, including a compression member, a tension member, and guide columns spaced at a greater distance at their bottom portions than at the upper portions thereof; of a bolster between said guide columns; a spring cluster of greater extent than the width of said bolster; means interposed between said bolster and said spring assembly to transmit the bearing stresses from the bolster to all portions of the spring cluster; rigid means connecting the widened portions of said guide columns, said bolster being insertible endwise between the narrow portions of said guide columns; and means for detachably retaining said bolster 115 120 125 130

in operative relation with said side frame.

25. In a railway truck, the combination with a side frame, including a compression member, a tension member, guide columns, and spring rest, said guide columns having relatively narrowly spaced portions accommodating a bolster, and relatively wider spaced portions for reception of bolster springs; a spring cluster including the maximum number of units receivable on said spring rest between the widened portions of said columns; means interposed between said bolster and spring cluster for distributing the bearing stresses of said bolster to all portions of said spring cluster; and rigid means connecting the lower portions of said guide columns, said tension member and said spring rest.

26. In a railway truck, the combination with a side frame, including a compression member, a tension member, guide columns and a spring rest, said guide columns having relatively narrowly spaced portions accommodating a bolster and relatively wider spaced portions for the reception of bolster springs; a spring cluster including the maximum number of units receivable on said spring rest between the wider portions of said column; means interposed between said bolster and spring cluster and guide columns for distributing the bearing stresses of said bolster to all portions of said spring cluster; rigid means connecting the lower portions of said guide columns, said tension member and said spring rest; a spring plank; a spring plate; and means extending through said rigid means and cooperating with said plate to hold said spring plank in operative position.

27. In a railway truck, the combination with a side frame, including a compression member, a tension member, and guide columns spaced a relatively great distance apart in proportion to the dimensions of the side frame; of a bolster positioned between said guide columns; a spring cluster of greater extent than the width of said bolster; means interposed between said bolster and said spring cluster and said guide columns to transmit the bearing stresses from the bolster to said spring cluster; rigid means connecting said guide columns adjacent the lower portions thereof, said bolster being insertible endwise between the upper portions of said guide columns; and means for detachably retaining said bolster in operative relation with respect to said side frame.

28. In a truck of the character described, the combination with a side frame having a compression member, a tension member and guide columns, said guide columns each having an offset portion at its lower end; a spring cluster having end springs extended into the offset portions of the guide columns; a bolster endwise insertible between

the upper ends of said guide columns; transmitting means interposed between said bolster and all of said springs; and detachable means cooperating with the bolster and guide columns for securing the bolster in position for up and down movements with respect to the side frame.

In witness that I claim the foregoing I have hereunto subscribed my name this 7th day of April, 1925.
